INTERLOCKING DEVICE FOR DISPENSING PUMPS

Filed Oct. 8, 1934

UNITED STATES PATENT OFFICE

2,120,645

INTERLOCKING DEVICE FOR DISPENSING PUMPS

Charles S. Hazard, New York, N. Y., assignor to
Neptune Meter Company, a corporation of New Jersey

Application October 8, 1934, Serial No. 747,379

13 Claims. (Cl. 221—95)

The present invention relates to interlocking devices and particularly to means for interlocking the resetting mechanism of a register with the operating means for the switch, or other control element, for the device with which the register is associated.

To afford an illustrative embodiment of the present invention its adaptation to a gasoline dispensing pump will be described herein. Gasoline dispensing pumps ordinarily have a meter-operated register that indicates the quantity of gasoline delivered to a customer and which is provided with a resetting mechanism operable to reset the indicating elements to their zero positions so that registration starts from zero when delivering gasoline to the next customer.

However, it has heretofore been possible to start the pump for dispensing fluid to a customer without having previously cleared the registration effected when dispensing gasoline to the previous customer. This failure to reset the register may occur due to the pump attendant's carelessness or because of an actual fraudulent intention on his part. As a result, the later customer may be charged for a part or all of the quantity of gasoline delivered to the previous customer, as well as for that which he actually receives. Such incidents would clearly be a source of customer dissatisfaction and, accordingly, it is desirable that precautions be taken to insure against their occurrence whether as a result of inadvertence or of fraudulent intention.

Some dispensing pumps are arranged so that when the delivery hose is removed from a hose supporting hook a switch controlling the pump-operating motor is actuated to start the motor to dispense gasoline, and when the hose is replaced on the hook the switch is automatically operated to stop the motor.

One of the principal objects of the present invention is to provide such a dispensing pump with means for interlocking the resetting mechanism of the register with the operating means for the switch controlling the operation of the motor that drives the pump by means of which gasoline or other liquid is dispensed.

Other objects and advantages of the invention will be apparent upon consideration of the following description and appended claims when read in conjunction with the accompanying drawing, in which

Figure 1 is a diagrammatic view of a liquid dispensing pump embodying the present invention;

Figure 2 is an enlarged rear view of the regis-

tering device and shows the resetting mechanism therefor;

Figure 3 is an enlarged view of a portion of the interlocking device shown in Figure 1;

Figure 4 is a sectional view taken along the line 4—4 in Figure 3; and

Figure 5 is an enlarged detail view of part of the resetting mechanism.

Referring to the drawing, the numeral 10 designates an electric motor for operating a pump 11 to withdraw gasoline from a suitable storage tank and force it through a hose 12 to the gasoline tank of an automobile or other point of delivery. The motor 10 is controlled by a switch 13 having an operating arm 14 connected by a link rod 15 to a pivoted hose hook 16. With this arrangement, when the hose is removed from the hook the switch may be moved to its "on" position for starting the motor to drive the pump and cause delivery of gasoline; replacement of the hose on the hook automatically moves the switch arm to its "off" position and stops the pump-operating motor. When the hose nozzle 17 is hung on hose hook 16 with the end portion of the nozzle extending into an opening or hood 18 in the pump casing, as diagrammatically illustrated in Figure 1, it prevents counter-clockwise movement of the hose hook and acting through link 15 locks the switch arm 14 against movement to its "on" position.

Interposed in the pipe connection between the delivery side of pump 11 and hose 12 is a meter 19 having a shaft for operating registering mechanism 20 to register the quantity of gasoline delivered from the pump.

The registering mechanism 20 may be any suitable construction and need neither be shown nor described in detail herein since the present invention is not concerned with its particular construction. As shown generally in the drawing, it may include a shaft 21 (Figure 2) which bears at its forward end one or more indicating hands 22 that sweep over the face of an indicating dial. A stop pawl 23 engageable with the shoulder of a cam 24 on shaft 21 is provided to stop the resetting movement of the hands at the zero point of the dial.

The resetting of the indicator hands of registers of this general type is usually accomplished by rotation of a knob in front of the glass 26 that protects the indicating hands and dial, the stem of the knob being projected through a hole in the glass and suitably connected to the shaft 21. An improved form of resetting mechanism suitable for use in conjunction with registering

devices of this type will be briefly described herein because it provides improved means of effecting the setting back of the indicator hands, avoids the necessity of making a hole through the glass cover of the dial and relieves the register and the meter entirely of the load of the set-back mechanism.

At the rearward end the shaft 21 carries a gear 30. One of the resetting gears to be mentioned, being normally out of engagement with the gear 30, is caused to move into engagement therewith in the first movement of resetting device and thereafter to rotate the gear 30 and the shaft 21 in a direction to reset the indicating hands. In the embodiment of the invention illustrated the setback gears 31, 32, 33 are mounted on a swinging arm 34, formed of two plates between which the gears are supported, the gear 33 being mounted on a shaft or spindle 35 supported in a suitable casting 36, secured to the casing 37 of the register mechanism. A flat, U-shaped spring 38 engaged between the headed end 40 of the shaft or spindle which supports the gear 31 and the adjacent plate 34 of the gear carrying arm, serves slightly to compress the two plates 34 against the gear 31 and thereby impose thereon a slight frictional resistance for a purpose to be explained.

The gear 33, of the train of gears 31-33, is engaged by a crown gear 41 carried by a shaft 42 which is supported in the casting 36 and arranged to be rotated in the resetting operation by any convenient means. As illustrated herein, the shaft 42 is geared to an actuating shaft 50 that is aligned with and operable by a drive shaft 51 provided with an operating handle 52.

Except when pressure is applied to the operating handle 52, the swinging arm 34 and the gear train carried thereby will move of its own weight from the position shown in full lines in Figure 2 to the position shown in broken lines, disengaging the gear 31 from the gear 30 and so relieving the register mechanism and meter of the load that would otherwise be imposed by the set-back gears. When it is desired to reset the indicating hands to the zero position the handle 52 is rotated. By reason of the slight frictional resistance imposed on the gear 31 the first effect of this action is to swing the arm 34 and the gear train to mesh the gear 31 with the gear 30. Continued rotation of the crown gear 41 will then effect rotation of the gears 31, 30 and shaft 21 until the indicating hands are stopped from further movement, as by the stop 23. As shown in Figure 5, the gear 31 is formed with a key 44 fitting in a slightly wider key-way 45 in the hub 46 on which the gear is mounted. This arrangement provides a small amount of lost motion between the gear 31 and the frictional means 38 that permits the gear to turn forward a small amount after resetting in order to facilitate disengagement of its teeth from the teeth of gear 30. The gear 30 is fixed to the shaft 21 so that the pawl 23 may act to stop the movement of actuating shaft 50 also, for a purpose mentioned later.

The inner end of shaft 51 is supported by a sleeve 53 connected to shaft 50 by a pin 54 and loosely mounted on shaft 51 by a washer 55. Mounted on contiguous portions of shafts 50 and 51 is an axially displaceable sleeve 56 provided with slots 57 engageable by antifriction rollers 60 carried by pin 54. Sleeve 56 carries a cam roller 61 engaging a cam 62 that is secured to the drive shaft 51 and adapted to displace the

sleeve 56 to the left. Sleeve 56 is also provided with a flange 63 for engaging and operating a bell crank 64 on such displacement of the sleeve. Bell crank 64 is connected by a link 65 to the switch operating arm 14 for moving the latter to its "on" position to start the motor 10.

A strong spring 66 mounted between a washer or collar 67 on shaft 51 and the web 49 of sleeve 56 forces roller 61 against cam 62. The cam 62 is formed with an abrupt shoulder 68 (Figure 3) normally in engagement with roller 61 so that drive shaft 51 on clockwise rotation may act through shoulder 68 and roller 61 to turn sleeve 56, the latter acting in turn through pin 54 to operate actuating shaft 50 for resetting the registering mechanism.

When the pointers of the registering device have been fully reset and stopped in their initial or zero positions by engagement of the shoulder of cam 24 with stop pawl 23, they act in conjunction with the latter to also terminate the operation of actuating shaft 50. Inasmuch as sleeve 56 is then held against rotation by pin 54, resistance is imposed to further operation of shaft 51. Incidentally, the encountering of this resistance indicates to the pump attendant that the registering mechanism is fully reset. When the force applied to turn drive shaft 51 is increased, the shoulder 68 of the cam is forced beyond the roller 61, thus disconnecting actuating shaft 50 from drive shaft 51. As the attendant continues to operate drive shaft 51 the rotation of cam 62 acting on roller 61 displaces sleeve 56 to the left, and its flange 63 operates bell crank 64 and switch 13 to start the motor 10 for dispensing gasoline through hose 12.

When rotation of the shaft 51 is discontinued spring 66 acts to displace sleeve 56 to the right, moving flange 63 away from bell crank 64 so that the motor switch may be moved to its "off" position when the hose is replaced on the hose hook 16. Spring 66 is preferably sufficiently powerful to turn shaft 51 if necessary, as in the event operation of the shaft should be inadvertently stopped while it is in a rotative position causing cam 62 to interfere with the movement of sleeve 56 to the right.

Reverse, or counterclockwise, rotation of drive shaft 51 before (or after) effecting resetting is not effective to cause displacement of sleeve 56 and hence can not result in improper operation of switch 13. On reverse rotation of shaft 51, spring 66 still presses roller 61 against cam 62, thus frictionally connecting sleeve 56 to shaft 51 for rotation therewith. The gear 31 on resetting arm 40 being held by gravity out of engagement with gear 30 (or swung from engagement therewith on reverse rotation of shafts 42 and 50 by sleeve 56) does not supply the resistance required to disconnect shafts 50 and 51 and cause cam 62 to displace sleeve 56 to the left, as described above. Consequently, reverse operation of drive shaft 51 would merely cause sleeve 56, actuating shaft 50 and the train of resetting gears 31-33 to be rotated idly.

For the purpose of avoiding damage to the mechanism in the event the resetting handle 52 is operated while the hose is on the hose hook, the bell crank 64 is preferably yieldingly connected to link rod 65, as illustrated in Figure 1, the spring 69 being of sufficient strength so as to yield to the movement of the bell crank only when considerable resistance is imposed.

The control switch 13 may be of the familiar spring-actuated toggle type. Such switches 75

have a spring and lever mechanism which holds the switch in either the "on" or "off" position after sufficient force has been applied to move the switch lever past center position and the spring is sufficiently strong to prevent improper operation of the switch through the medium of the weight of the bell crank 64 or connecting rods 15, 65, or accidental operation due to vibration.

From the foregoing description it may be seen that when the pump attendant has completed delivery of a quantity of gasoline to the customer, hung the delivery hose on the hose hook and thus automatically stopped the pump-operating motor, he cannot start the pump again to dispense gasoline to a succeeding customer until he has first reset the registering mechanism to clear the previous indication. The registering mechanism may be reset and the pump started in a single operation upon arrival of the later customer, or the register may be reset immediately on completing a delivery and the handle 52 further operated to actuate the interconnecting rod 65 so that the pump may be started when the later customer arrives. In either event, the possibility of the later customer being inadvertently or fraudulently charged for part or all of a previous delivery is eliminated due to the interlocking of the pump-controlling switch and the resetting mechanism of the register, as described herein.

Although an illustrative embodiment of the invention has been shown and described in detail, there are many changes and variations which may be made without departing from the invention and, accordingly, it is desired and intended to include all such changes and variations within the scope of the following claims.

I claim:

1. In a fluid dispensing device, means for dispensing fluid, an indicator for indicating the quantity of fluid dispensed and means associated with the dispensing means and indicator for resetting the indicator to zero and then initiating operation of the dispensing means, comprising a rotatable shaft for actuating said resetting means to reset said indicator to zero, a member on the shaft and movable axially thereof for initiating operation of the dispensing means and means actuated by said shaft for moving said member axially thereof only when the indicator is at zero.

2. In a fluid dispensing device, means for dispensing fluid, an indicator for indicating the quantity of fluid dispensed, zero stop means for the indicator, and means for resetting the indicator to zero and then initiating operation of the dispensing means, comprising a rotatable actuating shaft for resetting the indicator and a rotatable drive shaft normally movable with the actuating shaft, elements interposed between said shafts establishing driving relation therebetween so that both shafts are rotatable together through a plurality of revolutions and until the indicator has been stopped at zero by the zero stop means, means for maintaining said elements in driving relation, said elements being relatively movable against the action of said maintaining means when said indicator has been stopped at zero to disestablish said driving relation whereupon the actuating shaft is restrained from further rotation and the drive shaft is left free for further rotation, and means mounted on said drive shaft and movable axially thereof, during such further rotation, for initiating operation of the dispensing means.

3. In a fluid dispensing device, means for actuating the device, an indicator for indicating the quantity of fluid dispensed, zero stop means associated with the indicator, and means for resetting the indicator to zero and then initiating operation of the dispensing device, comprising a rotatable actuating shaft, a relatively rotatable drive shaft normally movable with the actuating shaft, a member supported on said shafts and relatively movable axially thereof, both shafts and the member being freely rotatable through a plurality of revolutions when the zero stop means is inoperative, and cooperating elements movable with said shafts and actuated by relative rotation thereof to produce axial movement of the member to initiate operation of the dispensing device.

4. In combination, a device having registering means, resetting means therefor, and means controlling the operation of the device; a drive shaft; an actuating shaft for said resetting means; means, releasably connecting said shafts to permit relative movement therebetween; a sleeve mounted on said drive shaft and displaceable axially thereof for operating said control means; camming means associated with said drive shaft and said sleeve for effecting said displacement of the latter upon relative rotation of the drive shaft and the actuating shaft; means associated with said drive shaft and said sleeve for preventing said displacement of the latter during operation of said actuating shaft by said drive shaft to reset said registering means; and means for stopping said registering means in the initial position thereof preventing further rotation of said actuating shaft and serving to render said camming means effective to displace said sleeve for operating said control means during subsequent operation of said drive shaft.

5. In combination, a device having registering means, resetting means therefor, and means controlling the operation of the device; an actuating shaft for said resetting means; a drive shaft for operating said actuating shaft; means releasably connecting said shafts for relative movement; a member mounted on said drive shaft and displaceable in one direction axially thereof for operating said control means; means associated with said drive shaft for preventing said displacement of said member during operation of said actuating shaft by said drive shaft to reset said registering means; means for stopping said registering means in the initial position thereof preventing further rotation of said actuating shaft for causing relative rotation of said actuating shaft and said drive shaft to take place on further movement of said drive shaft; means operable by said drive shaft upon such further movement thereof for effecting said displacement of said member to operate said control means; and means associated with said drive shaft and said member for displacing the latter in the opposite direction upon discontinuation of the operation of said drive shaft.

6. In combination a dispensing device having registering means and resetting means therefor, a shaft for operating said resetting means, means controlling the operation of the device, a rotatable member mounted for axial displacement on said shaft to operate said control means, means connecting said member to said resetting means for actuating the latter on rotation of said member, camming means actuated with said member and shaft adapted upon relative rotation thereof to effect axial displacement of said member.

means associated with said member and shaft for maintaining driving relation therebetween through said camming means during the resetting operation for preventing displacement of said member, and means for stopping said registering means in its initial position acting to prevent rotation of said member, thereby rendering said camming means operative to displace said member axially of said shaft to operate said control means.

7. In combination, a dispensing device having registering means, resetting means therefor and means controlling the operation of the device, a shaft for operating said resetting means, a rotatable member mounted on said shaft and displaceable axially thereof for operating said control means, means connecting said member to said resetting means for actuating the latter on rotation of said member, a cam and cam roller associated with said member and said shaft adapted on relative rotation thereof to cause said displacement of said member, means maintaining driving relation between said member and said shaft for rotating said shaft through the intermediary of said cam and roller, and means for stopping said registering means in its initial position serving to prevent further rotation of said member with said shaft, thereby rendering said cam and roller effective on further rotation of said shaft subsequent to resetting of said registering means to displace said member axially of said shaft to operate said control means.

8. In combination, a dispensing device having registering means, resetting means therefor, and means controlling the operation of the device; a shaft for operating said resetting means; a rotatable member mounted on said shaft and displaceable axially thereof for operating said control means; means connecting said member to said resetting means for actuating the latter on rotation of said member; a cam and cam roller associated with said member and said shaft adapted on relative rotation thereof to cause said displacement of said member; means maintaining driving relation between said member and said shaft for rotating said shaft through the intermediary of said cam and roller; and means for stopping said registering means in its initial position, to render said cam and roller ineffective to cause rotation of said member by said shaft and to render said cam and roller effective to cause axial displacement of said member to operate said control means upon operation of said shaft subsequent to resetting of said registering means.

9. In a dispensing system having a motor driven pump for dispensing liquid, means for registering the quantity of liquid dispensed, means for resetting said registering means, a delivery hose, a movable hose hook, and means for controlling said motor operable in response to removal of said hose from said hook to start said motor; means for operating said control means to start the motor; interlocking means asso-

ciated with said resetting means and said operating means for preventing actuation of the latter to start said motor until said resetting means has been actuated to reset said registering means; means connecting said hose hook to said control means for actuating the latter to stop said motor on movement of said hook by replacement of said hose thereon; and means for rendering said operating means ineffective to actuate said control means to start said motor when said hose is on said hose hook.

10. In a dispensing system having a motor driven pump for dispensing liquid, means for registering the quantity of liquid dispensed, means for resetting said registering means, a delivery hose, a movable hose hook, and means for controlling said motor connected to said hook, said control means being operable on removal of said hose from said hook to permit starting of said motor and operable by replacement of said hose to stop said motor; means for operating said control means to start the motor; and interlocking means associated with said resetting means and said operating means for preventing actuation of the latter to start said motor upon removal of said hose from said hose hook until said resetting means has been actuated to reset said registering means.

11. In a liquid dispensing device, means for establishing a flow of liquid, means for indicating the amount of liquid dispensed, means for resetting the indicator to zero, means for initiating operation of said flow establishing means, means for actuating said initiating means actuated by said resetting means upon continued operation thereof after the indicator has been reset to zero, and means preventing operation of the means for actuating said initiating means when said indicator is displaced from its zero position.

12. In a liquid dispensing device, flow establishing means, means for indicating the amount of liquid dispensed, means for resetting said indicator to zero including a stop member, means for connecting and disconnecting said indicator and resetting means, and means actuated by said resetting means and acting against said stop member through said resetting means when connected with said indicator for initiating operation of said flow establishing means.

13. In a liquid dispensing device, means for establishing a flow of liquid, means for indicating the amount of liquid dispensed, means for resetting said indicator to zero, stop means located in a position to be engaged by said resetting means only upon complete resetting of said indicator to zero and serving to resist further movement of said resetting means after said indicator has been reset to zero, means for initiating operation of said flow establishing means, and means for operating said initiating means actuated by said resetting means upon movement thereof against resistance imposed by said stop means.

CHARLES S. HAZARD.

CERTIFICATE OF CORRECTION.

Patent No. 2,120,645.

June 14, 1938.

CHARLES S. HAZARD.

It is hereby certified that error appears in the printed specification of the above numbered patent requiring correction as follows: Page 3, second column, line 21, claim 4, after "means" and before the semicolon insert the words "driven by said drive shaft"; and that the said Letters Patent should be read with this correction therein that the same may conform to the record of the case in the Patent Office.

Signed and sealed this 9th day of August, A. D. 1938.

Leslie Frazer
